To all whom it may concern:

Be it known that I, AARON E. CARPENTER, a citizen of the United States, and a resident of Philadelphia, Pennsylvania, have invented or 5 produced a new and original Design for a Background for Printed Matter, of which the following is a specification.

The design comprises representations of globes overlying one another, and having lines such as those indicative of latitude and longitude. As shown, the groundwork is colored 15 and the lines are white; but this arrangement may be reversed, if desired, or the ground may

be of one color and the lines of another color—color in this case implying something other than white.

I claim—
